UNITED STATES PATENT OFFICE.

CHARLES E. WAREAM, OF CINCINNATI, AND DANA H. BENJAMIN, OF CLEVELAND HEIGHTS, OHIO, ASSIGNORS TO THE AMERICAN LAUNDRY MACHINERY COMPANY, OF CINCINNATI, OHIO, A CORPORATION OF OHIO.

SHIRT-IRONING BOARD.

Original application filed July 2, 1917, Serial No. 178,286. Divided and this application filed March 21, 1921. Serial No. 454,212.

To all whom it may concern:

Be it known that we, CHARLES E. WAREAM and DANA H. BENJAMIN, citizens of the United States, residing at Cincinnati, Hamilton County, Ohio, and Cleveland Heights, Cuyahoga County, Ohio, respectively, have invented certain new and useful Improvements in Shirt-Ironing Boards, of which the following is a specification.

10 This invention relates to ironing machines, and more particularly to machines for ironing shirts.

The object of the invention is to provide an improved ironing machine embodying

15 an ironing board specially shaped to so iron the shirt that when folded up it will have the proper dress or set up and when worn will fit properly. More especially the invention has for its object to provide an im-

20 proved ironing board the ironing surface of which is convex at the neckband end, the side edges of said board diverging from the neckband end toward the tail end and the neckband end being provided with a back

25 yoke receiving member the surface of which is in a vertical plane or planes transverse to the length of the board and if desired inclined to a true transverse plane, all for the purpose of more accurately fitting the board

30 to the shirt to improve its appearance and avoid wrinkles or folds in the finished work.

Further objects of the invention are in part obvious and in part will appear more 35 in detail hereinafter.

The invention comprises the construction and arrangement of parts hereinafter described and claimed.

In the drawings, Fig. 1 is a plan view of 40 one form of ironing board embodying the invention; Fig. 2 is a cross section on the line 2—2, Fig. 1, the upper pressing member or head being also shown in dotted lines; Fig. 3 is a central longitudinal sectional 45 elevation on the line 3—3, Fig. 2; Fig. 4 is a plan view, on a larger scale, of the neckband former; Fig. 5 is a detail cross section on the line 5—5, Fig. 1; Fig. 6 is a detail sectional elevation on the line 6—6, Fig. 3; 50 and Figs. 7 and 8 are detail views, corresponding to Figs. 1 and 2, and showing modifications.

This application is a division of our prior application for ironing machines, Ser. No. 178,286, filed July 2, 1917, to which reference may be had for a more complete description if desired. 55

The stationary ironing head 1 is preferably heated, for which purpose its inner chamber 2 is supplied with heating medium 60 such as steam, through pipes 3. The lower or pressing face of the head is a plain metal surface 4 which is here shown as concave (Fig. 2) the surface of the board being correspondingly shaped, as will be readily understood. 65

The shirt receiving board 5 is supported by a hollow sleeve 6 which receives a post 7 depending from the base 8 of the board frame. Said sleeve has a lateral extension 70 9 which is provided with an opening to receive a rod or bar 10 depending from the base 8 and which permits the board and post to be moved vertically relative to the head for ironing purposes, but without relative rotation between head and board, thereby preserving their necessary and usual ironing registration with each other. 75

The base 8 is provided with upright webs 11 which carry a block 12 attached to the 80 under side of a longitudinal bar 13 lying in a recess of the board beneath the padding 14 thereon. This bar extends from the tail end of the board to the neckband end thereof where it is provided with recesses to receive vertical pins 15 which pass upwardly through recesses in the stationary forward portion 16 of the neckband former. The neckband former rises and falls on the pins 85 with the ironing motion, so as to allow the neckband former to sink with the padding when the ironing pressure is applied to the shirt, but the connection of the stationary member 16 of the neckband former to the bar 13 and its connection to the stationary 90 block 12 prevent any horizontal motion of member 16 relative to the stationary frame of the ironing board. Consequently when the shirt board is brought into registration 95 with the ironing head the curve of the front portion of the neckband former must register properly with the recess in the head. 100

The adjusting means for taking care of various sizes of shirts includes mechanism

for moving rearwardly the back portions of the neckband former. This arrangement maintains the folding line at the rear of the neckband former substantially tangent to the curve of the neckband former. The shirt board indicated at 17, Fig. 3, is attached to and carried by a frame 18 having side walls 19 and a base 20 which slides longitudinally in the direction of the length of base 8 (see Fig. 6). At one end said board carries a back yoke receiving form 21 from which rises a plate having a head 22 provided with a recess to receive a transversely extending rod 23 the ends of which enter openings in the back portions 24 of the neckband former. Said back portions are attached to pins or rods 25 which enter horizontal openings in the stationary portion 16, said openings diverging backwardly as shown in Fig. 4. When the frame 18 with the attached board 17 is moved rearwardly the rod 23 is carried back and moves with it the adjustable rear portions 24 of the neckband former, said portions moving diagonally as indicated in the dot and dash lines, Fig. 4.

The back yoke receiving form may be heated in any suitable manner, such as by conduction of electric current through leads 26 to a suitable electric heating element 27.

In this machine the shirt is pressed upon the board with the tails diverging. The neckband is preferably unbuttoned, its edges merely meeting or abutting. To clamp the ends of the neckband we provide a clamping member 28 having a body portion sliding in a recess 29 of member 16 and a flange 30 depending in front of the neckband former and adapted to clamp the neckband thereon. Said clamp member is pivoted to a rod 31 so as to have slight horizontal tilting motion relative thereto to accommodate itself to variations of thickness of the neckband. Rod 31 extends rearwardly through an opening in an L-shaped locking member 33 and then through an opening in an upwardly extending portion of a member 34 slidable longitudinally beneath the neckband former and provided with a recess 35 to receive the lower edge of member 33. A light compression spring 36 located behind member 33, tends to press it forward or to the right in Fig. 3. The opening in member 33 through which the rod 31 passes is slightly larger than said rod, so that when the vertical portion of member 33 assumes an askew position under the pressure of spring 36 member 33 grips the rod and prevents it from moving forwardly. However, pressure applied by the fingers to the clamping member 28 will push it backwardly into tight clamping position and at any time the clamp can be released by pressing down upon the horizontal portion of the member 33.

To secure a more powerful clamping action of member 28 the member 34 is pivotally connected to the upper arm of a lever 37 the pivot 38 of which has vertical motion in a slot in a stationary bracket 39 carried by the bar 13 and attached thereto by the pins 15 (Fig. 5). The lower arm of said lever is connected to a rod 40 normally moved rearwardly by a compression spring 41 and which is actuated through a compression spring 42 by a lever 43 pivoted at 44 on a shaft journaled in the stationary frame members 11. The actuating means for rod 40 is as follows:

45 is the actuating handle or lever which is secured to turn with a shaft 46 carrying a cam 47 and co-operating with an anti-friction member 48 on the lower arm of lever 43, and a gear segment 49 meshing with a gear segment 50 on a shaft 51 provided with an arm 52 carrying a roller 53. Roller 53 travels with lost motion between an abutment 54 on a bar 54^a extending across between walls 19 and an opposing abutment 55 on the movable frame 18. Arm 52 also has a laterally extending pin 56 which engages a depending arm 57 of a lever pivoted on a shaft 58 and having an arm 59 provided with a roller 60 lying beneath the horizontal arm 61 of a latch lever. Said latch lever has a depending arm 62 provided with a toe 63 lying at one side of rod 64 extending through guiding openings in the stationary frame member 8 and attached to bar 54^a. The toe 63 lies in front of a locking member 65 which has an opening through which the rod 64 passes and which is under the influence of a spring 66.

Fig. 3 shows the press in position ready to receive a shirt, the neckband former being contracted. The shirt is dressed upon the board with the neckband surrounding the neckband former and the clamp 28 is pushed back into clamping engagement with the neckband. Actuating lever 45 is then raised or turned in the counter-clockwise direction, Fig. 3. The first effect of the lever is to move roller 53 away from abutment 54 and pin 56 away from the lever arm 57. This allows arm 59 to drop, which in turn releases lever 61 and allows the toe 63 to move away from the spring pressed latch 65. At the same time cam 47 engages the roller 48 and oscillates lever 43 in the clockwise direction, thereby pulling on the rod 40 and moving back member 34 which carries with it rod 31 and applies powerful clamping pressure to the neckband clamp, said pressure however being limited to the pressure of spring 42. Finally the lost motion of roller 53 is completed and said roller engages abutment 55, whereupon further motion of the operative member moves back the movable frame 18 and with it the board 17, the back yoke receiving form 21, and

the back portions of the neckband former, thereby expanding said former within the neckband.

After the shirt has been pressed by relative vertical motion between the ironing board and pressing head the operating lever 45 is returned to its initial or normal position. The first motion of said lever produces lost motion or travel of arm 52

10 until pin 56 meets lever arm 57 which applies the toe 63 to the latch 65 and releases the rod 64. Further motion of said lever 45 moves the abutment 54 and 54^a to the right with corresponding motion of the 15 movable frame 18 and releases or contracts the neckband former. Finally the cam 47 returns to initial position and releases the powerful pressure upon the neckband clamp and after full release of said clamp by 20 pressing down upon the lock 33 the shirt can be removed from the board.

The ironing board may be of either of the forms shown in Figs. 1 and 2 or 7 and 8, and in either case should preferably be of 25 what is known as the "Keystone" type. In other words, its side edges 67 diverge from the neckband end of the board toward the tail end, as a consequence of which the shirt is dressed upon the board with the tails 30 spread and with the button and button-hole strips diverging. Also the upper or padded surface of the board is convex transversely, at least at the neckband end, the ironing head having either a convex surface on a 35 rounded curve, as shown in Fig. 8, or preferably its upper surface slopes laterally and downwardly toward each side from its longitudinal center line, as shown in Fig. 2.

The back yoke receiving form 21 is a 40 metal plate lying in substantially a vertical plane and extending across the full width of the shirt board. This plate may be truly transverse or may have its side portions inclined to a true transverse plane. For example, in Fig. 7, the planes of the side portions of the back yoke receiving form, indicated at 68, are inclined backwardly from the center of the board, whereas in Fig. 1 the side portions indicated at 68^a, are inclined forwardly, which is the preferable form. When the board is convex as described, the lower surface of the neckband former where it rests upon the padding, as at 69, is concaved to correspond. The lower 45 portion of the form 21 has a projection 70 which rides upon an adjacent stationary bracket member 71 to strengthen the form 21 against the pressure of the co-operating back yoke ironer, regardless of vertical 50 movement of the back yoke receiving form.

The advantages of the invention are as follows:

The desirability of inclining the side edges 55 of the board to "Keystone" form is well understood and enables the shirt to be

dressed upon the board with the tails spread or in diverging relation. However this arrangement upon a flat board was found to throw undesirable fullness or wrinkles in the front portions of the shirt at the neckband when the shirt is dressed upon the board. Construction of the back yoke receiving form with its ironing surface in a vertical plane or planes does not remove this fullness, even when the side portions of 70 the form are in planes inclined backwardly, as in Fig. 7. However, we have found that by bulging the board especially at the neckband end, all of this undesirable fullness 75 may be avoided and nevertheless the "Keystone" form may be retained and the back yoke receiving member can not only be in a vertical plane or planes but even in planes inclined forwardly, as in Fig. 1, so that the back yoke is ironed flat and the folding line 80 at the end edge of the board retains the desirable slope to either side. The entire arrangement enables the shirt to be so ironed that it will lie flat and without wrinkles or folds when folded up and has the 85 proper dress or set up and at the same time fits well when put on.

What we claim is:

1. In an ironing machine, an ironing board having a bosom receiving surface sloping laterally in both directions from its middle line in the region of its neckband, said board being sufficiently wide at the tail end and sufficiently narrow at the neckband end to support the side portions of the bosoms of various size shirts with the tails spread in diverging form from the neckband toward the tail end of the shirt, whereby those portions of the shirt adjacent to and at the sides of the neckband may be ironed smooth and without wrinkles. 95

2. In an ironing machine, an ironing board having a bosom receiving sloping laterally in both directions from its middle line in the region of its neckband, the side edges of said board diverging from the neckband end toward the tail end of the board, so as to support the side bosom portions of the shirt when arranged in diverging form from the neckband to the tail end of the shirt and with those portions of the shirt adjacent to and at the sides of the neckband in smooth unwrinkled form. 100

3. In an ironing machine, an ironing board having a bosom receiving surface sloping laterally in both directions from its middle line in the region of its neckband, and a back yoke receiving and ironing form at one end of said board having a vertical plane surface extending transversely to the 105 length of said board. 115

4. In an ironing machine, an ironing board having a bosom receiving surface sloping laterally in both directions from its middle line in the region of its neckband, 120

- and a back yoke receiving and ironing form at one end of said board having a vertical plane surface extending transversely to the length of said board, the side edges of said board diverging from the neckband end towards the tail end so as to support the bosom portions of the shirt when arranged in diverging form from the neckband to the tail end of the shirt.
- 10 5. In an ironing machine, an ironing board having a bosom receiving surface sloping laterally in both directions from its middle line in the region of its neckband, and a back yoke receiving and ironing form at one end of said board, the central portion of the surface of said back yoke receiving form lying in a transversely extending vertical plane, and the side portions of the surface of said back yoke receiving form lying in vertical planes inclined to the plane of the central portion thereof.
- 15 6. In an ironing machine, an ironing board having a bosom receiving surface sloping laterally in both directions from its middle line in the region of its neckband, and a back yoke receiving form at one end of said board, the central portion of the surface of said back yoke receiving form lying in a transversely extending vertical plane, and the side portions of the surface of said back yoke receiving form lying in vertical planes inclined to the plane of the central portion thereof and also inclined outwardly away from the tail end of the board.
- 20 7. In an ironing machine, an ironing board having a bosom receiving surface sloping laterally in both directions from its middle line in the region of its neckband, and a back yoke receiving and ironing form at one end of said board, the central portion of the surface of said back yoke receiving form lying in a transversely extending vertical plane, and the side portions of the surface of said back yoke receiving form lying in vertical planes inclined to the plane of the central portion thereof, the side edges of said board diverging from the neckband end towards the tail end, so as to support the bosom portions of the shirt when arranged in diverging form from the neckband to the tail end of the shirt.
- 25 8. In an ironing machine, an ironing board having a bosom receiving surface sloping laterally in both directions from its middle line in the region of its neckband, and a back yoke receiving form at one end of said board, the central portion of the surface of said back yoke receiving and

ironing form lying in a transversely extending vertical plane, and the side portions of the surface of said back yoke receiving form lying in vertical planes inclined to the plane of the central portion thereof, the side edges of said board diverging from the neckband end towards the tail end, so as to support the bosom portions of the shirt when arranged in diverging form from the neckband to the tail end of the shirt.

9. In an ironing machine, an ironing board having a bosom receiving surface sloping laterally in both directions from its middle line in the region of its neckband, and a back yoke receiving and ironing form at one end of said board, the central portion of the surface of said back yoke receiving form lying in a transversely extending vertical plane, and the side portions of the surface of said back yoke receiving form lying in vertical planes inclined to the plane of the central portion thereof and also inclined outwardly away from the tail end of the board.

In testimony whereof we hereby affix our signatures.

CHARLES E. WARREAM.
DANA H. BENJAMIN.
